[57] CLAIM

The ornamental design for a tape measure cover, as shown and described.

DESCRIPTION

FIG. 1 is a left front perspective view of a tape measure cover showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof.

The broken line showings of portions of an enclosed tape measure are environmental only and form no part of the claimed design.

FIG. 1.

FIG. 2.

FIG. 3.

FIG. 4.

FIG. 6.

FIG. 7.

FIG. 5.
